UNITED STATES PATENT OFFICE.

CHARLES W. WACHTEL, OF JAMAICA, NEW YORK.

PUSH-BUTTON.

No. 900,006.

Specification of Letters Patent.

Patented Sept. 29, 1908.

Application filed November 23, 1907. Serial No. 403,440.

To all whom it may concern:

Be it known that I, CHARLES W. WACHTEL, a citizen of the United States, residing at Jamaica, county of Queens, State of New York, have invented certain new and useful Improvements in Push-Buttons, of which the following is a specification, reference being had therein to the accompanying drawings, in which—

10 Figure 1 is a side elevation of the push button; Fig. 2 a horizontal sectional view on the line II—II of Fig. 1; Fig. 3 a plan view of the base piece; Fig. 4 a vertical transverse sectional view of the push button; and Fig. 5 a similar view of the supporting plate carrying the contacts.

This invention relates to new and useful improvements in push buttons for use in electric circuits.

20 One of the many objects of the invention is to provide such a device of simple construction which will be exceedingly durable, and which will give a positive and wiping contact between the two poles of the circuit.

25 In push buttons of the ordinary construction the contact is made by placing one piece of flat sheet metal in contact with another piece of similar material. These contacts are very unsatisfactory for the reason that 30 the slightest accumulation of dust and dirt between the two pieces of metal interrupts the current and makes an incomplete circuit. Another objection is that the flat pieces of metal soon lose their resilience and become 35 useless, particularly if they are exposed to changing atmospheric conditions.

Referring to the various parts by numerals, 1 designates a base plate having the upstanding annular flange 2 and an inward extending 40 annular flange 3. Fitting within the upstanding flange and resting on the flange 3 is a supporting plate 4 of hard fiber or other insulating material. The flange 3 is provided with a lug 5 which enters an opening in the 45 plate 4 to prevent the rotation of the plate, as is common in this class of device.

Secured to the plate 4 are two contacts 6 each of which consists of a screw having a head 7 and a shank 8 which is threaded 50 through the plate. The screws are placed a suitable distance apart and their heads constitute the contact points. On the shanks 8 are secured binding nuts 9 which not only serve to secure the circuit wires in place, but 55 also serve to securely hold the screws to the insulating plate. Pivoted in a slot in the

plate 4 is a movable contact-arm or lever 10, said arm being normally pressed outward or away from the plate by a spring 11 which is confined between the arm and the plate. 60 The contact-arm is provided at its free end with a contact-head 12 which is V-shaped in transverse section and is adapted to fit between the screw heads 7, the point of the contact-head being between the heads and the 65 inclined sides 13 thereof engaging the screw heads.

It will be readily seen that the contact head, in striking down between the screw heads, has a wiping contact with said heads so that the 70 points of contact will be at all times bright and clean and free from dust and dirt. The contact arm is pivoted in such manner that it will have a slight lateral movement on its pivot so that the contact head will, unless it is 75 pressed down very carefully between the two screw heads, contact with one of the screw heads before engaging the other. This will give a long sliding contact between the two parts, insuring bright, clean contact surfaces. 80

The contact arm and head are substantial in form so that they can be securely pivoted in the plate and cannot be injured in any way by rough usage or by exposure to the weather. 85

By providing the clamping screws, and arranging them to serve as a means for binding the circuit wires in place as well as the contact members, the device is very simple of manufacture and is very durable so that 90 it will last indefinitely.

The inclosing cap 14 is provided with slots 15 having the outwardly inclined surface 16. The flange 2 of the base plate is provided with pins or lugs 17 which are adapted to enter the 95 slots 15 and to engage the cam surface 16 whereby, upon the partial rotation of the cap 14, it will be securely clamped to the base plate. By this means I avoid the use of threaded connections between the flange 3 100 and the cap. The push button 18 is held in place by the cap its inner side resting upon the contact head 7 of the contact lever.

It will thus be seen that I provide an extremely simple, durable and efficient push 105 button; one that can be readily assembled.

Having thus described my invention, what I claim as new and desire to secure by Letters Patent, is:—

1. A push button comprising a plate of 110 insulating material, two contact points arranged thereon, means for connecting circuit

wires to said points, and a contact lever pivoted on said plate and provided with an angular portion adapted to engage the contact points carried by the plate, said contact lever being normally held away from the contact points.

2. A push button comprising an insulating plate a pair of screws threaded through said plate, binding nuts threaded on said screws and serving to connect the circuit wires thereto, the heads of said screws forming contact points, a pivoted contact lever formed with a contact head adapted to strike between the two contact points and to engage them, and means for normally holding the contact lever away from said contact points.

3. A push button comprising a plate of insulation, a pair of screws connected thereto, the heads of said screws forming contact points, means for connecting the circuit wires to said screws, a contact lever pivoted on said plate, and provided with an angular head adapted to strike between the heads of the screws, and to engage the same, and means for normally holding said lever away from the screw heads.

4. A push button comprising an insulating plate, a pair of screws threaded through said plate and provided with heads forming contact points, binding nuts threaded on said screws, a pivoted contact lever carried by said plate and formed with a transverse contact head at its free end, said head being V-shaped in cross-section, the lever being so arranged that the contact head will strike between the two screw heads and engage the

same, and a spring for normally holding the contact head away from the screw heads.

5. A push button comprising a base plate having an upstanding flange, a plate of insulation inclosed within said flange, a pair of screws carried by said plate of insulation, the heads of the screws forming contact points, a pivoted lever carried by the plate of insulation and provided with a transverse V-shaped contact head adapted to strike between the screw heads and to engage the same, means for normally holding the lever away from the screw heads, an inclosing cap provided with slots, one wall of said slot being cam-shaped and diametrically opposite pins extending radially from the upstanding flange of the base plate and adapted to fit in the slots of the cap, for the purpose set forth.

6. A push button comprising a supporting plate, two contact points arranged thereon and insulated from each other, means for connecting circuit wires to said points, a contact lever pivoted on said plate and formed with an angular head portion adapted to fit between and engage the contact points carried by the plate, and a spring for normally holding said contact lever away from the contact points

In testimony whereof I hereunto affix my signature in the presence of two witnesses this 21st day of November 1907.

CHARLES W. WACHTEL.
